175,714

GOBLET OR SIMILAR ARTICLE

Anthony De Bernardi, Brighton, and Mario Palombi,
Hyde Park, Mass.

Application February 1, 1954, Serial No. 28,766

Term of patent 7 years

(Cl. D36—8)

FIG. 1

FIG. 2

Fig. 1 is a side elevation of a goblet, showing our new design; and

Fig. 2 is a rear elevation thereof.

The dominant features of our design reside in those portions shown in full lines.

We claim:

The ornamental design for a goblet or similar article, as shown and described.
